UNITED STATES PATENT OFFICE.

CLARENCE RICHARD HILBERRY, OF FLINT, MICHIGAN.

TELEPHONE DIRECTORY.

1,426,566.

Specification of Letters Patent. Patented Aug. 22, 1922.

Application filed January 10, 1922. Serial No. 528,269.

To all whom it may concern:

Be it known that I, CLARENCE RICHARD HILBERRY, a citizen of the United States, and a resident of Flint, in the county of 5 Genesee and State of Michigan, have invented certain new and useful Improvements in Telephone Directories, of which the following is a specification.

My invention relates to improvements in 10 telephone directories, and it consists in the combinations, constructions and arrangements herein described and claimed.

An object of my invention is to provide a 15 telephone directory which is adapted to be applied to the transmitter of a telephone instrument and which affords facilities for presenting a plurality of names and the telephone numbers of the respective names to view selectively in such manner that the 20 selected name and telephone number thereof are disclosed in horizontal position and are spaced apart.

A further object of my invention is to 25 provide a telephone directory which is of maximum capacity for a directory of a given size.

A still further object of my invention is 30 to provide a directory of simplified construction, which is easy of operation, and which will enhance the appearance of a telephone instrument to which applied instead of detracting therefrom.

Other objects and advantages will be apparent from the following description, and 35 the novel features of the invention will be particularly outlined in the appended claims.

My invention is illustrated in the accompanying drawings, forming a part of this 40 application, in which:

Fig. 1 is a front view showing a telephone instrument equipped with a practical embodiment of the invention,

Fig. 2 is an enlarged view of a portion of 45 the mechanism shown in Fig. 1, illustrating the manner in which disks comprised in the device may be rotated to present a selected name and the number thereof to view,

Fig. 3 is a side elevation of the transmitter 50 of a telephone instrument and of the embodiment of the invention applied thereto.

Fig. 4 is an enlarged section of a fragmentary portion of the device, substantially

along the line 4—4 of Fig. 1, illustrating the manner in which selected disks or a selected 55 disk may be moved relatively to the remaining disks comprised in the device,

Fig. 5 is a view showing one of the disks upon which the names and telephone numbers thereof are provided,

Fig. 6 is a perspective view of a disk shifting member included in the device.

Fig. 7 is a view showing the disk shifting member in more or less developed condition,

Fig. 8 is a perspective view showing co- 65 operating front and back plates comprised in the form of the device now preferred by me, and

Fig. 9 is a view similar to Fig. 8 showing front and back plates of slightly modified 70 form.

Referring now to the drawings, 1 denotes a standard telephone instrument of the so-called desk type, which instrument is provided with a transmitter 2 having a mouthpiece 3 threadedly secured thereto. The frame or supporting structure of the embodiment of the invention illustrated comprises a front plate 4 of disk formation and a back plate 5 of like form. The front plate 75 4 has a hub portion 6 extending laterally of the rear face thereof, which hub portion is adapted to receive the inner end portion of the mouthpiece 3 and is provided with fastening lugs projecting from its ends and 80 adapted to engage slots in the back plate 5 which has a central opening 7 adapted to receive the threaded portion of the mouthpiece 3, whereby the front and back plates 85 may be coupled together while both are disposed upon the mouthpiece 3 and will be held contiguous to the transmitter 2 and against rotation relatively to the mouthpiece. In the form of the device now preferred by me, the fastening lugs have the 90 form illustrated in Figure 8 and are designated by the numeral 8. These lugs are projected through slots 9 which are formed through the back plate 5, as illustrated in Figure 8, and may then be bent against the 95 back plate 5 to prevent the said lugs disengaging the slots. In the form of front plate illustrated in Figure 9, lugs 10 of like formation are provided at the end of the hub 6. The front plate 6 will be held coupled 100 to the back plate 5 when the hook-like lugs

60

are projected through slots 11 in the latter and the front plate 4 is rotated to cause the hooks to engage the slots 11.

My invention contemplates the provision of a plurality of disks such as indicated at 12 in Figure 5. Each of these disks has a central opening 13 adapted to receive the hub 6, sufficient friction being created between contiguous disks and between the disks 10 and the front and back plates to normally hold the disks against rotation on the hub while permitting of such rotation under actuation of a slight force applied thereto. In the embodiment of the invention illustrated, a half portion of each disk 12 has a radius slightly less than that of the other half portion of the disk, thereby providing alined shoulders 14 and 15 at diametrically opposite points on the disk. Elongated 20 openings 16 and 17 respectively are formed through the disks on opposite sides of the central opening 13 and in alinement with each other and with the shoulders 14 and 15. A series of radially extending spaces 25 18 defined by lines marked on one face of the disk 12 extends in a clockwise direction from the opening 16 to the opening 17. A series of radially extending spaces 19 of greater extent than the spaces 18 and defined by lines marked on the same face of the disk 12 as hereinbefore mentioned, extend from the opening 17 to the opening 16. The number and arrangement of the spaces 19 correspond to the number and arrangement of the spaces 18, whereby corresponding spaces of the two series are alined.

A tab extension 20 extends radially from the outer edge of each disk 12 and bears a desired character, as for instance the letter 40 "H" shown in Fig. 5. In the embodiment of the invention illustrated, I provide a disk for each letter of the alphabet and each disk is like every other disk with the exception 45 that the tabs 20 of the respective disks are located at different distances from the shoulders 14, whereby all tabs 20 will appear in sequence when the disks are arranged upon the hub 6 in alphabetical order and the corresponding shoulders of the several 50 disks are in alinement, as illustrated in Fig. 1. The openings 16 of the several disks will then be in registry with one another and with an elongated opening 21 through the front plate 4. The openings 17 of the several 55 disks likewise will be in registry with one another and with an elongated opening 22 through the front plate 4, the openings 21 and 22 therefore being in alinement with each other. It is to be noted at this point 60 that the front plate 4 is by preference arranged upon the mouthpiece 3 so that the alined openings 21 and 22 lie in a horizontal plane. Each of the spaces 19 has produced thereon the name of a person whom it is 65 desired to list in the index and the space

18 in alinement with the space 19 has produced thereon the telephone number of the particular person. The numbers of the spaces 19 are arranged in alphabetical order reading counter-clockwise.

From the foregoing description of the various parts of the device, the operation thereof may be readily understood. When the device is in inactive position as illustrated in Figure 1, the corresponding opening through the front plate 4 and the several information-bearing disks 12 are in registry. Let us assume that it is desired to call a person whose name begins with "H". The fore-finger of the hand is then pressed against the tab marked "H" and the disk of which "H" is a part and the subsequent disks, are moved in a clockwise direction, while the preceding disks are held against movement by the other hand, the shoulders 14 thereof being held against an integral stop projection X formed on the rear plate to extend toward the front plate in spanning relation to the disks mounted on the hub 6. The stop X is illustrated to advantage in Figures 8 and 9. The movement of the disk "H" and the disks following "H" in order is continued until the desired name is observed through the inspection opening 21. The telephone number of the person whose name is disclosed through the opening 21 will be presented beneath the opening 22. The disks which have been moved will remain in the position to which moved until returned to original position. In Figure 4, certain of the disks 12 are shown as having been moved to active position while other disks have been held against movement so that the first of the moved disks may be observed through the opening 21 of the front plate.

Obviously, the disks 12 which have been moved may be returned to original position by hand but I preferably employ a disk shifting member in order to effect the return of the moved disks with economy in time and effort and with the desired precision. The disk shifting member is substantially of U-shape as illustrated in Fig. 6 and is made of a single metallic piece, such as shown in Fig. 7, which is bent to provide a web 23 adapted to span the outer edges of the several disks 12 and having a pair of parallel arms 24-24. The arms 24-24 are widened laterally in one direction at 25 and are provided with alined openings 26-26 located centrally of the widened portion. The openings 26-26 are adapted to loosely receive the hub 6 when the arms 24-24 are arranged to straddle the disks 12 on the hub 6 and the web 23 spans the peripheral edges of the several disks. The web 23 has an extension along one side edge, which extension is bent inwardly or toward the peripheral edges of the disks, as indicated at 27

and is adapted to contact the shoulders of the disks when moved relatively thereto, whereby a further movement of the arms 24-24 about the axis of the hub 6 in the 5 proper direction will occasion the return of the disk to original position. A struck-up portion 28 at the edge of the web 23 opposite to that provided with the extension 27 is provided for convenience in manipulating the disk shifting member since the 10 pressure of a finger upon the projection 28 will occasion a desired movement of the disk shifting member.

The front plate 4 is by preference provided with alined shoulders 29 and 30 with 15 which the shoulders 14 and 15 of the several disks 12 should be respectively alined when in inactive or original position, as illustrated in Fig. 1.

It will be understood that the front plate 20 4 and the back plate 5 may be made of any suitable material, such as a light metal or the parts may be made of a different material. For example, the face of the front 25 plate 5 may be covered with leather as illustrated. The information disks 12 are preferably made of paper or like material and as these disks are protected at all times in the manner hereinbefore described, no appreciable wear thereon will result from the 30 continued use of the device.

It will be apparent that I have provided a telephone directory of very simple construction which is operable at will to present 35 desired information to a user of the device in such manner that the possibility of error in reading the desired information, is reduced to a minimum. Obviously, my invention is susceptible of embodiment in 40 forms varying in detail from that described and illustrated herein and that I therefore consider as my own, all modifications and adaptations of the illustrated form of the device which properly fall within the spirit 45 and scope of the invention as outlined in the appended claims.

I claim:—

1. A telephone directory comprising a front plate having a hub projecting laterally 50 of the rear face thereof, said front plate being provided with alined spaced apart openings therethrough, a plurality of disks rotatably mounted on the hub and each provided with alined openings therethrough 55 respectively adapted to register with the corresponding openings of the front plate when the disks are in a certain position with respect to the front plate, each of said disks having desired data produced thereon in 60 position to be observed through the said openings when the particular disk is rotated relatively to the front plate, and means carried by the hub for maintaining the disks on the hub and for permitting of the rotation 65 of the said disks.

2. A telephone directory comprising a front plate having a hub projecting from the rear face thereof, said front plate having alined openings therethrough at diametrically opposite points and being provided 70 with alined shoulders on the outer periphery thereof, a plurality of disks rotatably mounted upon the hub and each being provided with alined openings therethrough adapted to respectively register with the 75 corresponding openings through the front plate when the disks are in a certain position with respect to the front plate, each of said disks having alined shoulders on its periphery respectively alined with the corresponding shoulders of the front plate when the corresponding openings of the disks and front plate are in registry and having desired data produced thereon in position to be 80 observed through the said openings of the front plate when the disk is rotated relatively to the latter, and means associated with said hub for preventing axial movement of said disk while permitting the rotation thereof.

3. A telephone directory comprising a front plate having a hub projecting from the rear face thereof, said front plate having alined openings therethrough at diametrically opposite points and being provided 90 with alined shoulders on the outer periphery thereof, a plurality of disks rotatably mounted upon the hub and each being provided with alined openings therethrough adapted to respectively register with the 95 corresponding openings through the front plate when the disks are in a certain position with respect to the front plate, each of said disks having alined shoulders on its periphery respectively alined with the corresponding shoulders of the front plate when the corresponding openings of the disks and front plate are in registry and having desired data produced thereon in position to be 100 observed through the said openings of the front plate when the disk is rotated relatively to the latter, and means associated with said hub for preventing axial movement of said disk while permitting the rotation thereof.

4. A telephone directory comprising a front plate having a hub projecting laterally of the rear face thereof, said hub having a bore adapted to receive the mouthpiece portion of a telephone instrument and said front plate have alined openings therethrough at diametrically opposite points and alined shoulders on its periphery in the plane of the openings, a plurality of disks rotatably mounted on the hub and each having alined openings and shoulders on its periphery, the respective openings of each disk being adapted to be positioned in registry with the corresponding openings of the front plate when the respective shoulders 110 115 120 125 130

of the disk are in alignment with the corresponding shoulders of the front plate, each of said disks having two series of characters produced thereon, corresponding characters of the two series being presented to view simultaneously through the said aligned openings of the front plate and having related values, and an outwardly extending integral identification tab extension for each disk.

5. A telephone directory comprising a front plate having a hub projecting laterally of the rear face thereof, said hub having a bore adapted to receive the mouthpiece portion of a telephone instrument and said front plate having aligned openings therethrough at diametrically opposite points and aligned shoulders on its periphery in the plane of the openings, a plurality of 10 disks rotatably mounted on the hub and each having aligned openings and shoulders on its periphery, the respective openings of each disk being adapted to be positioned in registry with the corresponding openings of 15 the front plate when the respective shoulders of the disk are in alignment with corresponding shoulders of the front plate, each of said disks having two series of characters produced thereon, corresponding 20 characters of the two series being presented to view simultaneously through the said aligned openings of the front plate and having related values, an outwardly extending integral identification tab extension for each 25 disk, and a disk shifting member rotatably mounted upon said hub and having a portion adapted to engage the shoulders of the said disks for moving the latter into alignment with the corresponding shoulder of 30 the said front plate.

6. A telephone directory comprising a front plate having a hub projecting laterally of the rear face thereof, said hub having a bore adapted to receive the mouthpiece portion of a telephone instrument and said front plate having aligned openings therethrough at diametrically opposite points and aligned shoulders on its periphery in the plane of the openings, a plurality of 45 disks rotatably mounted on the hub and each having aligned openings adapted to register with the corresponding openings of the front plate at times and shoulders on its periphery respectively adapted to be positioned in alignment with the corresponding shoulders of the front plate when the disks are in the said positions, each of said disks having two series of characters produced thereon, corresponding characters 50 of the two series being presented to view simultaneously through the said aligned openings of the front plate and having related values, an outwardly extending in-

tegral identification tab extension for each disk, a disk shifting member comprising a 65 web portion adapted to span the edges of the disks and parallel arms having aligned openings therethrough adjacent to their ends adapted to receive the said hub, said web portion having an extension bent inwardly and adapted to engage the shoulders of said disks when the disk shifting member is rotated relatively to the disks, and a back plate connected to said hub to hold the said disks against axial movement 70 or permitting of the rotation thereof, said back plate having an opening therethrough adapted to substantially register with the bore of the hub and to receive a portion of the mouthpiece of a telephone instrument 75 and having a stop projection arranged to engage corresponding shoulders of the said disks.

7. A telephone directory comprising a frame adapted for attachment to the mouth piece of a telephone instrument and including a front plate having aligned openings therethrough at diametrically opposite points and aligned shoulders in the plane of the openings, and a plurality of 80 juxtaposed disks rotatably supported by the frame and each having aligned openings and shoulders on its periphery, the respective openings of each disk being adapted to be positioned in registry with the corresponding openings of the front plate when the respective shoulders of the disk are in alignment with the corresponding shoulders of the front plate, each of said disks having two series of characters produced thereon, corresponding 85 characters of the two series being presented to view simultaneously through the said aligned openings of the front plate and having related values.

8. A telephone directory comprising a 90 frame adapted for attachment to the mouth piece of a telephone instrument and including a front plate having aligned openings therethrough at diametrically opposite points and aligned shoulders on the periphery in the plane of the openings, a plurality of disks rotatably supported upon the frame in concentric relation to the front plate, each of said disks having shoulders on its periphery respectively adapted to be 95 positioned in alignment with the corresponding shoulders of the front plate at times and having two series of characters produced thereon, corresponding characters of the two series being presented to view 100 simultaneously through said aligned openings and having related values, and a disk shifting member supported on the frame and having a portion adapted to engage the shoulders of said disks to rotate the latter.

CLARENCE RICHARD HILBERRY.
